INTELLECTUAL PROPERTY

(57) **CLAIM**

The ornamental design for a divot repair apparatus as shown and described.

DESCRIPTION

FIG. 1 is a bottom plan view of the ornamental design for a divot repair apparatus in an open configuration;

FIG. 2 is a top plan view in an open configuration;

FIG. 3 is a left side elevation view in an open configuration;

FIG. 4 is a bottom perspective view in an open configuration;

FIG. 5 is a bottom plan view of the counter-rotating divot repair apparatus in a closed configuration;

FIG. 6 is a top plan view in a closed configuration;

FIG. 7 is a left side elevation view in a closed configuration;

FIG. 8 is a bottom perspective view in a closed configuration;

FIG. 9 is a bottom perspective view of the divot repair apparatus shown in a partially opened or closed configuration;

FIG. 10 is a bottom plan view, with the divot repair apparatus shown in a partially open or closed configuration;

FIG. 11 is a bottom perspective exploded view, with the divot repair apparatus shown in a partially opened or closed configuration; and,

FIG. 12 is a top perspective exploded elevation view, with the divot repair apparatus shown in a partially opened or closed configuration.

1 Claim, 12 Drawing Sheets
